UNITED STATES PATENT OFFICE.

JOSEPH MARDER, OF SWISSVALE, PENNSYLVANIA.

DESIGN FOR A BOTTLE.

Application filed August 6, 1926. Serial No. 18,622. Term of patent 7 years.

To all whom it may concern:

Be it known that I, JOSEPH MARDER, a citizen of the United States, residing at 1202 Braddock Avenue, city of Swissvale, in the county of Allegheny and State of Pennsylvania, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

JOSEPH MARDER.
